ELECTRIC TOOL-DRIVER.

No. 852,926.

Specification of Letters Patent.

Patented May 7, 1907.

Application filed December 21, 1905. Serial No. 292,828.

To all whom it may concern:

Be it known that we, ALLEN F. CARVER and JAMES N. STOUT, citizens of the United States, and residents of the borough of Manhattan, in the city and State of New York, have invented a new and useful Electric Tool-Driver, of which the following is a specification.

Our invention relates to electric tool drivers and more particularly to an electric tool driver in which a reciprocating hammer is caused to deliver blows in rapid succession on a tool holder by the energizing and de-energizing of electromagnet coils.

The objects are to provide an auxiliary switch in connection with the handle of the tool for operating an electromagnet to make and break the current to throw the driver into and out of operation; to provide means for utilizing the return stroke of the hammer to cool the electromagnet coils; to provide a tool holding chuck which shall co-operate with the hammer to increase the magnetic force and decrease the cost of the tool proper; to provide simple and efficient means for holding the switch block and its housing plate in position and to provide means for materially reducing the eddies of magnetic current in both the hammer and shell.

With these objects in view, our invention consists in certain features of construction and combinations of parts as will be herein-after described and pointed out in the claims.

In the accompanying drawings, Figure 1 is a view of the tool driver in longitudinal section, Fig. 2 is a transverse section in the plane of the line A—A of Fig. 1, Fig. 3 is a partial side elevation of the handle partly broken away, Fig. 4 is a top plan of the same with housing plate removed, Fig. 5 is an end view of the hammer proper, Fig. 6 is an enlarged transverse section of the shell, and Fig. 7 is a diagrammatical view showing the electrical connections between the several coils, switches, commutators and source of electrical energy.

The driver consists of an outer shell 1, an inner tube 2, spaced from the outer shell, a series of coils, in the present instance three, denoted by 3, 4, and 5, located between the shell 1 and inner tube 2, a foot piece 6 interlocked with the foot end of the shell and provided with a stem 7 extending within the foot

end of the inner tube and a handle 8 held in engagement with the head ends of the shell and inner tube by an annular nut 9.

The handle is hollow and has fixed therein a block 10 of insulating material carrying two contact plates 11 and 12 spaced apart and arranged to be bridged by a piece of conducting material 13 on the inner end of a plunger 14 seated in the handle and provided with a retracting spring 15, which tends to hold the bridge piece 13 out of contact with the plates 11 and 12 when pressure is removed from the plunger.

The block 10 is held in position by the single bolt 16 which passes through the handle and serves to hold, at the same time, the housing plate 17 in its position. The housing plate 17 is further held against displacement by pins or studs 18 projecting outwardly from the side of the body of the handle and arranged to enter holes or sockets 19 in the plate.

The handle 8 is provided with a hollow stem 20 which projects into the head end of the shell, receiving therein the head end of the inner tubes 2 and furnishing a seat for the reciprocating piston 21, the latter having located within its hollow outer end a cushioning spring 22 for moving the piston away from the head of the stem 20.

The space between the piston 21 and the head of the stem 20 is in effect a dash pot the compressed air from which is directed to the exterior of the electromagnet coils through discharge ducts, in the present instance three denoted by 23, 24, 25. The number of ducts may be increased or diminished at pleasure. Air is admitted to the dash pot through a duct 26 extending through the base of the handle.

The several ducts 23 to 25 inclusive, are provided with spring actuated discharge valves 23*, the spring pressure on which is sufficient to permit the valves to open when the air pressure within the dash pot reaches a predetermined point. The duct 26 is also provided with an inlet valve 26*.

The foot piece 6 is provided with a central bore 27 for receiving the shank 28 of the tool holder 29. The outer end of the tool holder is provided with a socket 30 for the reception of the shank of the tool 31. The tool may

be a riveting set or any other tool and may be held in position in the tool holder by any suitable means, for example, by means of a pin 32.

- 5 The inner end of the shank 28 of the tool holder is provided with an enlarged head 33, of some material highly receptive of magnetic influence. This head 33 may be secured in any suitable manner, for instance, 10 by means of a cross pin 34. The head 33 is located within the field of the driving magnet coil 4 and serves to materially increase the force of the hammer blow by attracting the hammer and in turn to promptly repel the 15 hammer when the demagnetizing coil is energized. This head also serves to increase area of the surface which receives the impact of the hammer and thus decreases the tendency to upset the metal.
- 20 The hammer proper is denoted by 35. It is preferably an elongated cylinder, of iron or steel and is provided with radial cuts 36 extending longitudinally from one end to near the opposite end, the said cuts being filled 25 with suitable insulating material and serving to break up what are known in the art as current eddies. The shell 1 is in like manner cut longitudinally as at 37 to interrupt the current eddies which may form in it.
- 30 The contact pieces 11 and 12 carried by the block 10 are electrically connected with the opposite poles of an electromagnet 38, in the present instance, a solenoid, by wires 39 and 40, one of said wire sincluding a source 35 of electric energy shown conventionally at 41. The solenoid closes and opens a switch 42, for energizing the several coils to set the driver in operation.

A commutator shown conventionally at 43 40 is represented as having two segmental contact plates 44, 45, along the faces of which the contact arm 46 travels to regulate the current through the coils.

It is to be understood that the arm 46 may 45 be rotated by any well known or approved means, for instance by an electric motor, not shown.

The arm 46 is electrically connected with one pole of the generator 41 by a wire 47 including the switch 42 and the opposite pole of the generator is connected with the plates 44, 45, through the coils 3, 4 and 5, as follows:—A wire 48 leads from the generator to the coil 5, the wire 48 forming an electric 55 continuation of the wire 39 leading to one of the contacts of the auxiliary switch herein above referred to. From the opposite pole of the coil 5, a wire 49 leads to the demagnetizing coil 3, and from its opposite pole a wire 60 50 leads to the plate 44 of the commutator. The wire 48 by means of a branch wire 51 also connects with one pole of the driving coil 4, its opposite pole being connected by a wire 52 with the commutator plate 45.

65 The coil 3 is, for convenience, termed the

de-magnetizing coil, since, either by its reverse winding or by directing the current through it, in a direction opposite that in which the current is passed through the other coils, it serves, when energized to set 70 up in the tool holder a repellent force for releasing the hammer as soon as its blow has been delivered.

The coil 4 is termed the driving coil as it is relied upon to draw the hammer toward the 75 tool holder to deliver the blow.

The coil 5 is termed for convenience the reTRACTING coil as it is relied upon in conjunction with the coil 3 to withdraw the hammer.

The arrangement is such that the hammer 80 never moves out of a position to be influenced by the coils 4 and 5, and the enlarged head of the tool holder is in position to be influenced by the coil 4 so that when the coil 4 is energized it sets up corresponding polarity in 85 both the hammer and the tool holder which brings unlike poles toward each other in the hammer and tool holder thereby increasing the effective blow of the hammer.

The return movement of the hammer also 90 operates the piston 21 compressing its spring 22 and also the volume of air behind it forcing the air out through the ducts 23, 24, 25, around the coils, within the shell, from whence it escapes through suitable outlet 95 openings 53 in the shell.

In operation, the operator by pushing the plunger 14 inwardly and closing the space between the plates 11 and 12 energizes the solenoid 38 and closes the main switch 42. This, 100 assuming the parts to be in the position shown in Figs. 1 and 7, energizes the coils 3 and 5 and the hammer will be retracted, striking the cushioning piston 21 and ejecting the cooling medium. As the arm 46 travels 105 off the plate 44 the coils 3 and 5 will be de-energized and as the arm 46 engages the plate 45 the coil 4 will be energized and the hammer caused to deliver its blow assisted by the attraction of the head 33. As the 110 arm 46 leaves the plate 45, the coil 4 will be de-energized and as the said arm engages the plate 44 the coils 3 and 5 will be again energized and the hammer retracted.

While we have chosen to illustrate three 115 coils in connection with the driver, it is to be understood that the number of coils may be changed to suit the requirements of any particular driver.

What we claim is:—

1. In an electric tool driver, the combination with a series of magnetic coils, a reciprocating hammer within the coils and means for supplying an electric current to energize the coils, of a solenoid switch for 125 making and breaking the main current to energize the coils, contacts in the handle of the electric tool driver electrically connected with the poles of the solenoid and means for closing the contacts in the said handle to en- 130

ergize the solenoid and hence operate the switch in the main circuit.

2. In an electric tool driver, including electromagnet coils for advancing and retracting the hammer, a dash-pot comprising a spring actuated reciprocating piston in position to receive the impact of the hammer on its return stroke.

3. In an electric tool driver, including electromagnet coils for advancing and retracting the hammer, a dash pot comprising a spring actuated, reciprocating piston in position to receive the impact of the hammer on its return stroke, and ducts for admitting air to the dash pot and for discharging it around the coils.

4. In an electric tool driver, including electromagnet coils for advancing and retracting the hammer, a dash pot comprising a spring actuated, reciprocating piston in position to receive the impact of the hammer on its return stroke and valved ducts for admitting air to the dash pot and for discharging it around the coils.

25 5. In an electric tool driver including electromagnet coils for advancing and retracting the hammer, a movable tool holder having

its inner end within the field of the hammer driving coil.

6. In an electric tool driver, including electromagnet coils for advancing and retracting the hammer, a tool holder having an enlarged head on its inner end within the field of the hammer driving coil.

7. In an electric tool driver including electromagnet coils for advancing and retracting the hammer, a tool holder having an enlarged head on its inner end within the field of a coil and a tool receiving socket in its outer end.

8. In an electric tool driver, a block of insulating material carrying contact plates and seated in the handle, a housing plate removably fitted to the side of the handle and a bolt extending through the block and plate and serving to hold both in position.

In testimony, that we claim the foregoing as our invention, we have signed our names in presence of two witnesses, this 18th day of December 1905.
